UNITED STATES PATENT OFFICE.

RICHARD L. GUION, OF ELMIRA, NEW YORK.

ELECTRIC HEAT-REGULATOR.

SPECIFICATION forming part of Letters Patent No. 355,164, dated December 28, 1886.

Application filed April 7, 1886. Serial No. 198,075. (No model.)

To all whom it may concern:

Be it known that I, RICHARD L. GUION, of Elmira, in the county of Chemung, in the State of New York, have invented new and useful Improvements in Automatic Heat-Regulators, of which the following, taken in connection with the accompanying drawings, is a full, clear, and exact description.

The purpose of this invention is to automatically regulate the temperature of the interior of buildings, or of incubators or other structures or apparatuses; and the invention consists in the novel combination, in an electric circuit, of a clock-work having a cam-wheel, a switch for opening and closing the circuit operated by said cam-wheel, electro-magnets, an armature adapted to engage and stop the clock-work, and a latch actuated by the cam-wheel and adapted to retain the armature out of engagement with the clock-work, all as herein-after more fully described, and specifically set forth in the claims.

In the annexed drawings, Figure 1 is a face view of my invention with the front plate of the frame or case of the clock-work removed; and Fig. 2 is a vertical transverse section on line $x-x$, Fig. 1, the spring and main gear through which said line passes being omitted to obviate confusion in the view presented.

30 The same letters of reference indicate the same or corresponding parts.

A represents a metallic frame or clock-case, on which is mounted the following clock-work: A main driving-wheel, 1, receives its motive power from a coiled spring, 2, connected with the shaft s of said wheel and with the frame A. This wheel 1 meshes in a pinion, 3, on a shaft, P, as represented by dotted lines in Fig. 1. Said shaft P is extended across the frame and projects at opposite sides thereof, and has connected to its ends pulleys or cranks C C, which, by means of chains or cords c or other suitable devices, are connected with the dampers or valves of a heating apparatus designed to be automatically controlled by the rise and fall of the temperature in the apartment deriving heat from said heating apparatus. On the shaft P are also fastened a cam-wheel, o, and a gear-wheel, 4, which latter meshes in a pinion, 5, secured in common with a gear-wheel, 6, on a shaft, s' ,

pivoted on the frame. The wheel 6 engages a pinion, 7, on another shaft, s' , pivoted to the frame, and a gear-wheel, 8, on the latter shaft meshes in a pinion, 9, secured to the pivoted shaft s' , to which the fly-wheel h is attached. The described train of gearing, however, may be varied according to the speed required of the shaft P, to which the motion is to be transmitted. The cam-wheel o has two sets of cams, one of which consists of a single pin, m, projecting from one side thereof, and the other set consists of two pins, n n, projecting from the opposite side.

Horizontally across the upper part of the wheel o, at the side from which the pins n n project, is a latch, j, pivoted at one end to a suitable support on the frame A, and having its free end formed with steps or shoulders u u' at different distances from the end, for the purpose hereinafter explained. The intermediate portion of the latch is provided at its under side with a downward-projecting cam, j', which is encountered by the pins n n during the rotation of the wheel o, and thus lifts the free end of the latch.

a a represent electro-magnets, and d is the armature, which is pivoted, as at y, at or near the end adjacent to the wheel o, and has rigidly attached to said end an upright arm, d', upon the upper end of which the free end of the latch rests by one of the steps u. The armature is supported clear of the magnets by a spring, f, and when so supported the armature engages the fly-wheel h, so as to stop the rotation thereof, and consequently stop also the movement of the entire clock-work. At the same time the arm d' is lowered and swung toward the wheel o to allow it to engage the inner shoulder, u', of the latch j, which shoulder merely serves as a stop to limit the movement of the armature toward the fly-wheel, as represented by full lines in Fig. 1 of the drawings. When the electric circuit is completed through the magnets a a, the armature d is drawn down and caused to release the fly-wheel h, thus allowing the clock-work to run. In the said movement of the armature the arm d' thereof is swung to bring the upper end under the outer shoulder, u, of the latch, and as the pin n of the wheel o moves from under the cam j' of the latch, the latter drops and causes its

outer shoulder, u , to catch on the upper end of the arm d' , and thereby retain the armature d out of engagement with the fly-wheel h . A half-revolution of the wheel o brings the 5 succeeding pin n under the cam j' , and thereby raises the latch and releases the arm d' . The electric circuit through the magnets having in the meantime been broken, as hereinafter described, allows the spring f to draw the armature into engagement with the fly-wheel h , and thereby stop the motion of the clock-work; hence it will be observed that the shaft P , on which the wheel o and the cranks $C C$ are mounted, receives only a half-revolution at a 10 time. The electric circuit through the magnets $a a$ is controlled by the following instrumentalities:

On the frame A is pivoted a lever or switch, e , one end of which is bifurcated, and has the 15 two arms thereof straddling the shaft P and pin m of the cam-wheel o ; so that during the rotation of said wheel the pin m thereof imparts an oscillatory movement to the lever e . In the path of the oscillation of the opposite 20 end of the lever are two binding-posts, $i' i''$, attached to the frame A and insulated therefrom and arranged in such relative positions as to come in contact with the said end of the lever e at the extremities of its oscillations. 25 The pin m is so arranged in relation to the pins $n n$ as to cause the former to carry the lower end of the lever e in contact with the binding-post i'' while one of the pins n moves from under the cam j' of the latch j .

30 T denotes a thermostat, which is to be located in the apartment in which the heat is to be automatically controlled. Said thermostat may be of any suitable style. For the purpose of illustration I have selected a thermostat of 35 the class described in another application for Letters Patent, filed March 11, 1886, Serial No. 194,782. It consists of a bar, B , which is supported stationary at one end, and has its free end adapted to deflect laterally under the influence of heat. Said bar is composed partly 40 of metal and partly of rubber, and its support is also composed of metal, and on said support, at opposite sides of the free end of the thermostatic bar B , are two electric contact-points, $e' e''$, which are insulated from the metallic support of the bar B . A wire, s , is 45 extended from the contact-point e' to the binding-post i , and another wire, s' , is extended from the contact-point e'' to the binding-post i'' , heretofore referred to, and a third wire, s'' , is extended from the metallic support of the thermostat to one pole of the battery D . A wire, s''' , leads from the other pole of the 50 battery to a binding-post, m' ; wires s'''' and t connect the battery with the metallic frame A , the current passing from the frame through wire t , magnets a , wire s'''' , and wire s''' to the battery.

The operation of my invention is as follows: 55 As the heat in the apartment containing the thermostat T rises above the desired temperature, the thermostatic bar B deflects and

comes in contact with the contact-point e'' , and thereby closes the electric circuit through the wire s' and binding-post i'' , and thence 70 through the switch-lever e and metal frame A to the magnets $a a$, and thence through the wire s'''' to the binding-post m' , and from thence by wire s''' to the battery D . The circuit, being thus completed, causes the magnets $a a$ to draw down the armature d , and thereby releases the fly-wheel h and allows the 75 clock-work to run. The engagement of the arm d' of the armature with the outer shoulder, u , retains the armature in its said position until the wheel o has made a half-revolution, when one of the pins n thereof lifts the latch and releases the arm d' . The switch-lever e , having in the meantime been removed 80 from the binding-post i'' by the pin m of the wheel o , and the circuit thus broken, allows the armature to be drawn up by the spring f and thrown into engagement with the fly-wheel h , to stop the motion of the clock-work. During this movement the cranks $C C$ on the 85 shaft P are turned so as to both close the valve or damper, which admits the draft to the fire of the heating apparatus, and open a check-damper, admitting air to the smoke-pipe of the same, thereby cooling the apartment heated 90 by said apparatus. This change of temperature allows the thermostat T to resume its normal condition, and thus break the electric circuit. When the temperature falls below a certain degree, the thermostatic bar B is drawn 95 over against the contact-point e' and again closes the electric circuit, the clock-work being thereby again set in motion to impart a partial revolution to the shaft P , and thereby turn the aforesaid valves, so as to increase 100 the draft through the fire of the heating apparatus.

It is obvious that my invention can be arranged to also open and close the valves of steam-heating apparatus, so as to automatically control the flow of steam to the radiators located in the apartments to be heated.

Having described my invention, what I claim as new, and desire to secure by Letters Patent, is—

1. In an electric circuit, a clock-work having a cam-wheel, a switch for opening and closing the circuit operated by said cam-wheel, electro-magnets, an armature adapted to engage and stop the clock-work, and a latch actuated by the cam-wheel and adapted to retain the armature out of engagement with the clock-work, as set forth.
2. In an electric circuit, a clock-work having a cam-wheel with two sets of cams, a switch-lever adapted to open and close the circuit and operated by one set of said cams, a latch operated by the other set of cams, electro-magnets, and an armature held normally in engagement with the clock-work to stop the motion thereof, and adapted to engage the latch when attracted by the magnets, substantially as set forth.
3. In an electric circuit, the combination of

a clock-work, electro-magnets, the armature, a spring for drawing the armature in engagement with the clock-work, a cam-wheel having two sets of cams, a latch actuated by one set of said cams and adapted to retain the armature out of engagement with the clock-work, an oscillatory switch-lever actuated by the other set of cams, and binding posts in the path of said lever at the extremities of the oscillations thereof, substantially as described and shown.

4. In an electric circuit, the combination of a thermostat having electric contact-points brought in contact under the influence of heat, a clock-work having a cam-wheel with two sets of cams, an oscillatory switch-lever actuated by one set of cams, binding-posts in the path of said lever, electro-magnets, a pivoted

armature, a spring for drawing the armature into engagement with the clock-work to stop the motion thereof, and a latch actuated by the other set of cams and adapted to retain the armature out of engagement with the clock-work, and cranks or pulleys on the shaft of the cam-wheel, substantially as described and shown.

In testimony whereof I have hereunto signed my name and affixed my seal, in the presence of two attesting witnesses, at Elmira, in the county of Chemung, in the State of New York, this 9th day of March, 1886.
